MECHANICAL HAMMER

Benjamin W. Snodgrass, Denver, Colo.

Application December 4, 1934, Serial No. 755,907

4 Claims. (Cl. 255—42)

This invention relates to mechanical hammers, and more particularly to mechanical hammers of portable type adapted to operate tool elements such as drills, chisels, formers, hammers, and the like, and has as an object to provide an improved arrangement and assembly of elements effective to operate such tool elements in a practical and efficient manner.

A further object of the invention is to provide improved means for actuating a reciprocating impact element in a mechanical hammer.

A further object of the invention is to provide improved means for operatively interconnecting rotary power means and a reciprocable impact element in a mechanical hammer.

A further object of the invention is to provide an improved arrangement and assembly of elements for operatively mounting a reciprocable impact element in a mechanical hammer.

A further object of the invention is to provide improved means automatically operable by the impact element actuating means to rotate the shank of a tool cooperating with a mechanical hammer.

A further object of the invention is to provide improved means automatically operable by the impact element actuating means to feed a tool and mechanical hammer assembly toward the work to be performed.

A further object of the invention is to provide an improved mechanical hammer susceptible of practical development in a variety of specific forms, readily adaptable to a wide variety of specific uses, positive and efficient in operation, relatively simple and inexpensive of manufacture, and requiring a minimum of maintenance in use.

My invention consists in the construction, arrangement and combination of elements herein-after set forth, pointed out in my claims and illustrated by the accompanying drawings, in which—

Figure 1 is a longitudinal section axially of a hammer assembly embodying the principles of the invention. Figure 2 is a cross section, on an enlarged scale, taken on the indicated line 2—2 of Figure 1. Figure 3 is a cross section, on the same scale as Figure 2, taken on the indicated line 3—3 of Figure 1. Figure 4 is a fragmentary detail section of and at right angles to the showing of Figure 3. Figure 5 is a fragmentary detail section, on the same scale as Figure 2, taken axially of an air piston employed in the assembly according to Figure 1. Figure 6 is a longitudinal section axially of an improved hammer assembly

modified somewhat in respect of the showing of Figure 1. Figure 7 is a cross section, on a scale enlarged relative to Figure 6, taken on the indicated line 7—7 of the latter figure. Figure 8 is a cross section, on the same scale as Figure 7, taken on the indicated line 8—8 of Figure 6. Figure 9 is a fragmentary detail section, on a further enlarged scale, illustrating certain details of the showing of Figure 8. Figure 10 is a longitudinal section axially of an improved hammer assembly still further modified in respect of the showing of Figure 1. Figure 11 is a cross section, on a scale enlarged relative to Figure 10, taken on the indicated line 11—11 of the latter figure. Figure 12 is a fragmentary detail section of friction drive means employed in the assembly according to Figure 10. Figure 13 is a fragmentary detail elevation of and at right angles to the showing of Figure 12. Figure 14 is a longitudinal section axially of an improved hammer assembly yet further modified in respect of the showing of Figure 1. Figure 15 is a detail cross section taken on the indicated line 15—15 of Figure 14.

In the construction of the improved hammer as illustrated in Figures 1 to 5, inclusive, the numeral 20 designates a suitable frame member, preferably formed as a hollow cylinder, arranged to support and house the operative elements of the assembly. One end of the member 20 is closed, as by means of a removable plate 21, and suitable means, such as a T-handle 22, is provided adjacent the closed end of the member 20 whereby the assembly may be conveniently manipulated. Positioned in axial alignment within and adjacent the closed end of the member 20, an armature 23 of an electric motor assembly is mounted for rotation in suitable bearings carried by said member 20, the complementary magnetic poles or fields of the motor assembly being indicated at 24 surrounding the armature 23 in fixed relation within the member 20 to complete a power unit carried by and housed within said member, aligned with the armature 23, a relatively long, tubular impact element 25 is positioned axially within the member 20 and floatatively mounted for free rotation and reciprocation relative to said member in suitable spaced anti-friction bearings 26 carried by said member. The end of the element 25 adjacent the armature 23 is closed save for a splined central aperture arranged to slidably receive a splined portion of the extended armature shaft 23', thus engaging the element 25 and armature 23 for simultaneous rotation and feath-

ering the former to the latter for relative axial reciprocation therebetween, the opposite end of the element 25 being closed by means of a preferably replaceable impact head 27. To utilize 5 rotation imparted to the element 25 by the armature 23 to effect reciprocation of said element, an annular race or track 28 is fixed to the member 20 between the bearings 26 in surrounding relation with the element 25, said race 28 10 being provided with a plurality of uniformly-spaced cam bosses 29 projecting from that race surface most nearly adjacent the motor assembly and arranged to cooperate with a freely rotatable cam follower 30 carried exteriorly of 15 the element 25 on a stud or spindle fixed to and projecting radially from said element, so that, as the element 25 is caused to rotate, the cam follower 30 is caused to traverse the race 28 and ride over the cams 29 thereof, each said cam 20 imparting axial displacement to the said element 25 in the direction of the motor assembly. Travel of the element 25 in the direction of the motor assembly is limited and reverse travel of said element initiated by a resiliently yieldable member, 25 illustrated in this instance as a frusto-conical sheet spring 31, fixed within the member 20 adjacent the race 28 in surrounding relation with the element 25 and in the path of an annular flange 32 fixedly carried by said element 25, the 30 resiliently yieldable member being arranged for compression toward and expansion away from the motor assembly, so that motion of the element 25 toward the motor assembly results in engagement of the flange 32 with the resilient member 31, compression of the latter, limitation of the travel of the moving element in the one direction and initiation of travel of said element in the opposite direction through recovery of the resilient member, thus establishing a complete 35 cycle of reciprocation for the said element 25. The tool element to be acted upon by the impact element 25 is illustrated as a drill shank 33 loosely mounted in axial alinement with the said element 25 through a bore formed for that purpose in the terminal extension 20' of the member 20, said shank 33 being provided with an annular stop flange 33' arranged to limit extension of said shank within the portion 20' and adapted to be engaged at times by a retaining fork 34 40 hinged to the portion 20' in position to embrace the shank 33 and prevent accidental unseating of the latter. Within the portion 20' of the frame and positioned adjacent the normally-located inner shank end, a second resilient element in 45 the form of a frusto-conical sheet spring 35 is arranged in the path of the impact head 27 and in surrounding relation with the shank 33 to receive and absorb impact of said head when said shank is dismounted or whenever overtravel of the impact element might result from any cause. When the hammer assembly is to be employed in drilling operations, it is desirable that 50 means be provided operable to jet air through and to the working face of the drill tool, such means being illustrated as comprising a piston 36 closely fitted within and freely reciprocable axially of the hollow impact element 25, said element being provided with an air inlet 37 adjacent its non-impact end and said piston being provided with suitable air passages 38 controlled by a check valve 39 arranged to utilize the inertia effect of said piston during reciprocation of the impact element to jet air through a bore in 55 the impact head 27 registering with a longitudi-

dinal bore of the drill tool upon impact engagement of said head with said tool.

In the modified construction of the improvement as illustrated in Figures 6 to 9, inclusive, the operating elements are substantially the same 5 in function and interrelation as previously set forth and are modified only in respect of certain additions and equivalent substitutions. In the modified construction, the frame member 20 and motor elements 23 and 24 are the equivalents of 10 and may be identical with those above described, but the handle 22 is omitted and the member 20 slidingly mounted on and arranged for travel along a fixed feed frame 40, which latter is swiveled, as at 41, to a suitable tripod or other mount, 15 as is common practice. The frame 40 includes a longitudinally disposed, fixed lead screw 42 engaged by an internally-threaded pinion 43 carried by the frame member 20 concentrically with and for travel along said screw 42, said pinion 20 20 meshing with a gear 44 fixed to the armature shaft 23' for rotation therewith within the member 20, to the end that rotation of the armature 23 shall act through the gear 44 and pinion 43 to move the latter along the screw 42 and thereby 25 advance the member 20, with its included elements, along the frame 40. The impact element 25, mounting bearings 26 and head 27 of the modification are substantially, and might well be 30 actually, identical with those above described, but in the modification the element 25 is spaced somewhat from the armature shaft 23' and is connected to the latter for rotation therewith by means of an axial stem 45 fixed to said element 25 and terminating in a splined or angular head 46 slidingly received within a complementary bore formed in the said shaft 23'. The race 28, cams 29 and follower 30 of the modification correspond closely with those elements as first 35 described and cooperate to the same end, but the resilient element of the modification is illustrated as an expansive coil spring 47 surrounding the stem 45 and positioned in the member 20 between the gear 44 and impact element 25 and arranged for end engagement by the latter, the function 40 and action of said spring 47 being essentially identical with the function and action of the previously described resilient element 31. As shown 45 in Figures 6 and 8, a separate tool holder or chuck 48 is rotatably carried in the impact end 50 of the member 20, said chuck being arranged to loosely receive the tool shank 33 and being provided with radial notches wherein radial webs 49 formed on the tool shank 33 are engaged to rotatably interconnect the chuck and tool shank. 55 As one means of automatically rotating the chuck 48, spirally inclined segmental surfaces 50 are shown formed on an inner face of the chuck body, which faces are adapted to be engaged at the end of an impact stroke of the element 25 by the ends of pins 51 carried in axial 60 parallelism by and extending from the impact head 27.

In the modification according to Figures 10 to 13, inclusive, is illustrated an improved hammer 65 assembly particularly adapted for use in stoping operations common to mining. As shown in Figure 10, this modification employs an impact element 25 provided with the annular flange 32 mounted for actuation within the frame 20 in the 70 manner shown in Figure 1 and hereabove described. In place of the resilient element 31 of Figure 1, an expansive coil spring 47' similar to the element 47 of Figure 6 is employed in the manner and for the purpose described for the 75

element 31, the track 28, cams 29 and follower 30 being included to function as hereabove set forth, and the non-impact end of the element 25 is splined to one end of an extended armature shaft 23' for rotation therewith and travel axially thereof. The tool shank 33 is mounted in and extends loosely through a chuck 52 rotatably carried in and adjacent the impact end of the member 20, said chuck being formed with or having secured thereto a star wheel 53 with which a radial lug or finger 54 fixed to a shaft 55 rotatably disposed longitudinally of the member 20 is adapted to cooperate in such manner as to advance the star wheel one point for each revolution of the shaft 55, thus intermittently rotating the chuck 52 and tool element carried thereby. To rotate the shaft 55, a friction cone 56 is splined to the armature shaft 23' between the motor assembly and element 25 and is yieldingly positioned axially of said shaft 23' by means of an expansive coil spring 57 engaging between said cone 56 and an annular rib fixed to said shaft 23', and a complementary friction cone 58 is splined to the shaft 55 and yieldingly positioned thereon by means of an expansive coil spring 59 engaging between said latter cone and an annular flange 60 fixed to the shaft 55, so that, as the element 25 approaches the impact end of its stroke, the friction surfaces of the cones 56 and 58 are brought into engagement to transmit rotation of the former to effect rotation of the latter and consequently of the shaft 55, the yieldable positioning of the said cones permitting disengagement of and slipping between their friction surfaces whenever resistance to rotation of the chuck 52 is encountered. To advance the hammer assembly in the direction of drilling operations, a tubular sleeve 61 is mounted for rotation and held against axial displacement in and axially of a conical extension 62 of the member 20 secured to and projecting axially from the motor end of said member. The sleeve 61 is provided with a star wheel 63 secured to its inner end and an internally-threaded portion adjacent its outer end, and a threaded stem 64 threadedly engages within said sleeve and is formed with a bearing point 64' feathered through and projecting beyond the outer end of the extension 62, so that rotation of the sleeve 61 in one direction acts, through its threaded engagement therewith, to axially extend the bearing point 64' through the frame extension 62 and consequently urge the hammer assembly away from the bearing engaged by the point 64'. To rotate the sleeve 61, the shaft 55 is extended past the motor assembly and provided with a second radial finger or lug 65 positioned in operative relation with the star wheel 63 and arranged to act through the friction drive of the cones 56 and 58, above described, to intermittently advance said star wheel 63 and rotate the sleeve 61.

In the modified construction illustrated in Figures 14 and 15, rotation of the armature 23 is transmitted through suitable bevel gears 66 and 67 to effect rotation of a shaft 68 disposed transversely of the member 20 adjacent the motor assembly, said shaft being provided with a plurality of cam lobes 69 disposed in a common plane radially thereof and arranged to operatively engage a cam follower 70 rotatably carried on the end of a stem 71 extending in fixed relation from the impact element 25 through a fixed guide 72 carried by the member 20, so that rotation of the shaft 68 acts through the lobes 69, follower 70

and stem 71 to actuate the element 25 toward the motor assembly and into end engagement with the resilient coil spring element 47 disposed in the member 20 in surrounding relation with the stem 71 and intermediate the shaft 68 and impact element 25. The modification is provided with the rotatable chuck 52, star wheel 53, radial finger 54 and shaft 55 illustrated in Figure 10 and hereabove described, said shaft 55 in this instance being provided with a terminal friction cone 73 10 yieldingly held by means of an expansive coil spring 74 in driven relation with a friction cone 75 mounted on and for rotation with the shaft 68. An impact block 76 is mounted for limited axial motion in the member 20 adjacent the chuck 52 and is arranged to bear against the inner end of the tool shank 33 and transmit to said tool shank impact received from the element 25, said block 76 being formed with a peripheral channel communicating through radial bores 77 20 with a central port 78 adapted to register with the air bore of the tool shank, so that air supplied to the peripheral channel of the said block may be led to and for discharge through the said air bore of the tool shank. To supply air to the 25 peripheral channel of said block, an air pump in the form of an impeller 79 secured to the shaft 68 within a chamber carried within the member 20 is arranged to draw air through suitable ports 80 formed in the member 20 and discharge said 30 air, under pressure, through a conduit 81 connecting said chamber with the peripheral channel of the said block 76.

It will be noted that all of the constructions illustrated and described provide mechanical 35 means for converting rotary motion of an integral power unit to effect reciprocation of an impact element, said reciprocation being generated and maintained by power actuation of the impact element in the direction of and against a 40 resilient element for reaction therefrom, free of mechanical restraints, to work effect on a relatively fixed, elastic element, and consequent reaction after work effect in the direction of repeated power acceleration, the various specific 45 embodiments of the invention illustrated being all effective to the same end and each presenting a practical and operable construction for a complete, portable, powered, mechanical hammer unit that is highly efficient in operation and 50 adaptable to a wide variety of uses in the field.

Since the various mechanical refinements and adjuncts of the improved hammer illustrated and described in connection with specific embodiments of the invention may be employed with and applied to other embodiments of the said invention, and since modification of and variation in the specific form, construction and arrangement of the elements shown and described may be had without departing from the spirit and essence of 60 the said invention, I wish to be understood as being limited solely by the scope of the appended claims, rather than by any details of the illustrative showing and foregoing description. 65

I claim as my invention:

1. In a mechanical hammer, a casing having front and rear sections, a power unit mounted in the rear portion of the rear section, a rotatable chuck at the front end of the front section, a tool having a bored shank extending through said chuck into the front section and having an impact block at its rear end formed with air passages leading from the bore of the tool shank, an impact member freely slideable longitudinally in the front section towards and away from the im- 75

- pact block and having a stem extending into the rear section and provided with a follower at its rear end, a spring in the rear end of the front section about said stem spaced from the rear end 5 of the impact member for the major portion of movement of the impact member and engageable by the rear end of said impact member to check rearward movement of the impact member and impart rebound thereto, a driven shaft rotatably 10 mounted in the rear section transversely thereof, a spiral cam carried by said shaft for engaging said follower to shift the impact member rearwardly during rotation of the shaft, a fan housing in the rear section, a fan in said housing carried by said driven shaft, an air conduit leading 15 from said housing to the forward end portion of said front section for delivering air to the air passages of said impact block, means for imparting rotation to said shaft from said power unit, 20 and means for transmitting rotary motion from the driven shaft to the chuck.
2. In a mechanical hammer, a casing having front and rear sections, a power unit mounted in the rear portion of the rear section, a rotatable 25 chuck at the front end of the front section, a tool having a bored shank extending through said chuck into the front section and having an impact block at its rear end formed with air passages leading from the bore of the tool shank, an 30 impact member freely slideable longitudinally in the front section towards and away from the impact block and having a stem extending into the rear section and provided with a follower at its rear end, a spring in the rear end of the front 35 section about said stem spaced from the rear end of the impact member for the major portion of movement of the impact member and engageable by the rear end of said impact member to check rearward movement of the impact member and 40 impart rebound thereto, a driven shaft rotatably mounted in the rear section transversely thereof, a spiral cam carried by said shaft for engaging said follower to shift the impact member rearwardly during rotation of the shaft, a fan housing 45 in the rear section, a fan in said housing carried by said driven shaft, an air conduit leading from said housing to the forward end portion of said front section for delivering air to the air passages of said impact block, a friction disk 50 carried by said driven shaft, a friction disk carried by said power unit and engaging the friction disk of said shaft for imparting rotation to the shaft from the power unit, a transmission shaft extending longitudinally through the front 55 section and into the rear section, means for trans-

mitting rotation from the friction disk of said driven shaft to said transmission shaft, and means for intermittently transmitting rotation from said transmission shaft to said chuck.

3. In a mechanical hammer, a casing having front and rear sections, a power unit mounted in the rear portion of the rear section, a rotatable chuck at the front end of the front section, a tool having a bored shank extending through said chuck into the front section and having an impact block at its rear end formed with air passages leading from the bore of the tool shank, an impact member freely slideable longitudinally in the front section towards and away from the impact block and having a stem extending into the rear section and provided with a follower at its rear end, resilient means in the rear end of the front section spaced from the rear end of the impact member for the major portion of travel thereof and engageable by the impact member to 15 check rearward movement of said impact member and impart rebound thereto, a driven shaft rotatably mounted in said rear section driven from said power unit and carrying a cam member for engaging the follower and shifting the impact 20 member rearwardly, a source of air under pressure in said rear section actuated by said driven shaft, an air conduit leading from the source of air under pressure to the front end of said front section for delivering air to the air passages of the impact block, and means for imparting rotation to the chuck.

4. In a mechanical hammer, a casing, a power unit in the rear portion of said casing, a chuck at the front end of said casing, a tool having a shank extending through said chuck into the casing, an impact member freely slideable longitudinally in said casing towards and away from the rear end of the tool shank, a stem for said impact member extending rearwardly in said casing, a cup mounted in said casing about said stem, a spring in said cup spaced from the rear end of said impact member for the major portion of movement of the impact member and engageable by the rear end of the impact member to check rearward movement of the impact member and impart rebound thereto, a driven shaft rotatably mounted in said casing and rotated from said power unit, a cam carried by said shaft, and a follower carried by said stem for engaging said cam whereby reciprocating motion will be imparted to said impact member during rotation of said driven shaft.
